UNITED STATES PATENT OFFICE.

JOHN D. MEENAN, OF RIDGWAY, PENNSYLVANIA.

AUTOMATIC CAR-BRAKE.

SPECIFICATION forming part of Letters Patent No. 288,719, dated November 20, 1883.

Application filed June 16, 1883. (No model.)

To all whom it may concern:

Be it known that I, JOHN D. MEENAN, of Ridgway, Elk county, in the State of Pennsylvania, have invented a new and useful Improvement in Automatic Car-Brakes; and I do hereby declare that the following is an accurate description of the same, having reference to the accompanying drawings, wherein—

Figure 1 is a perspective view of my device. Fig. 2 is a side elevation of the same. Fig. 3 is a transverse section.

The object of my invention is to make a brake which may be caused to act automatically, or be thrown out of action at will; and it consists, essentially, in a lever interposed between a bumper-rod and the brake-rod, and movable fulcrum for said lever, which may be put in position or removed at will.

A is the car-bumper, and a is a bumper-rod passing back through or near to said bumper A, and supported in proper bearing, which permits said rod to slide endwise. A strong spring, i, forces said rod forward to its normal position. When the cars of a train come in contact by reason of resistance at the front of the train, the bumper-rod a is forced inward, and when the mechanism is in gear the brakes are thereby forced against the wheels.

The device which I have employed in connection with the bumper-rod a, to embody my invention, consists of a lever, e, jointed at one end to the bumper-rod a, and at its other end to the brake rod or chain q. When the bumper-rod is forced inward, the one end of said lever is carried with it, and if, at that moment, said lever is in contact with a stationary abutment or fulcrum, it becomes a lever of the first order, and the brake chain or rod q will be pulled in an opposite direction, and the brakes thereby forced against the wheels with a force proportionate to the force with which the bumper-rod a is forced inward. The requisite fulcrum is the latch-bar f, which at one end is pivoted at g to some stationary part of the frame of the car, and at its other or free end is adapted, when in position, to engage the arm e and act as a fulcrum for it. I therefore put the pin h in the arm e, and make a notch, n, in the latch f, so that when said latch is in one position the pin h will engage in the notch n, and will become a lever, and when the latch f is withdrawn from that position lever e will

not be so engaged, and will be merely a freely- 55 swinging arm. The latch f is provided with a link, o, and means whereby said latch may be moved into or out of position at will.

The above is a description of a typical structure, embodying my invention, of a removable fulcrum for the lever, whereby motion is communicated to the brakes, so that they may be made automatic or non-automatic at will. The details of structure may be greatly varied, and therefore I do not propose to limit 65 myself to the details shown.

I think it preferable to make the lever e with two parallel parts, as shown in Fig. 2, with the latch f passing through between them. This avoids all torsional strain when 70 in action.

The link o is connected with a latch-bar p, which, however, is capable of descending independently of said link, so that when it is desired to leave the wheels locked by the brake 75 said latch-bar p is left at liberty, and when the bumper-rod a is pushed in, and the brakes thereby applied, said latch-rod drops in front of a shoulder or stop, x, on said bumper-rod, and prevents its return outward when released 80 from pressure of the car in front.

Having described my invention, what I claim as new is—

1. An automatic car-brake consisting of a sliding bumper-rod, a, and a lever or arm, e, 85 jointed at one end to the brake rod or chain q, and at the other end to the sliding bumper-rod a, and provided with the pin h, combined with a pivoted latch-arm, f, with notch n, adapted to act as a fulcrum for said lever when in 90 position, and means for raising said latch out of position at will.

2. The bumper-rod a and the arm e, jointed at one end to said rod and at the other end to the brake rod or chain q, combined with the 95 latch f, jointed at one end to the frame of the car, and provided with the latch n and lifting-link o, as set forth.

3. The sliding bumper-rod a, provided with a shoulder, x, the lever e, pivoted at one end 100 to said rod, and at the other end to the brake rod or chain q, combined with a lifting-link, o, and the latch p, substantially as set forth.

JOHN D. MEENAN.
